DESIGN FOR A TEXTILE FABRIC OR SIMILAR ARTICLE

Michael Ginson, Ann Arbor, Mich.

Application October 4, 1938, Serial No. 80,240

Term of patent 3½ years

To all whom it may concern:

Be it known that I, Michael Ginson, a citizen of the United States and a resident of Ann Arbor, in the county of Washtenaw and State of Michigan, have invented a new, original, and ornamental Design for a Textile Fabric or Similar Article, of which the following is a specification, reference being had to the accompanying drawing, forming part thereof. The figure is a plan view of a textile fabric showing my design.

I claim:

The ornamental design for a textile fabric or similar article, as shown.

MICHAEL GINSON.
